UNITED STATES PATENT OFFICE.

CHARLES M. HEID, OF ERIE, PENNSYLVANIA.

SIGNAL APPLIANCE FOR MOTOR-VEHICLES.

1,359,476.

Specification of Letters Patent. Patented Nov. 16, 1920.

Application filed June 7, 1917. Serial No. 173,351.

To all whom it may concern:

Be it known that I, CHARLES M. HEID, a citizen of the United States, residing at Erie, in the county of Erie and State of

5 Pennsylvania, have invented certain new and useful Improvements in Signal Appliances for Motor-Vehicles; and I do hereby declare the following to be a full, clear, and exact description of the invention, such as 10 will enable others skilled in the art to which it appertains to make and use the same.

The present invention relates to electrical switches, and the object of the invention is the provision of a novel and improved switch 15 device controlling an electrical motor for operating a reciprocatory member, whereby the successive operations in closing an electrical circuit will result in said member being moved back and forth, such as for operating a signal member of a vehicle semaphore or the like.

With these and other objects in view as will appear as the description proceeds, the invention comprises the various novel features of construction, combination and arrangement of parts as will be more fully described hereinafter and set forth with particularity in the appended claims.

Referring to the drawings,

30 Fig. 1 is a horizontal sectional view through the device.

Fig. 2 is a perspective view of the slidable bracket arm or member and switch plate carried by it.

35 Fig. 3 is a vertical sectional view taken on the line 3—3 of Fig. 1, looking in the direction of the arrow.

Fig. 4 is a similar view showing the trip arm in the act of releasing one of the spring 40 latches.

Fig. 5 is a vertical sectional view taken on the line 5—5 of Fig. 1.

Fig. 6 is a top plan view of the switch plate showing the contacts thereon.

45 Fig. 7 is a top plan view of the contact plate with which the switch plate co-operates.

Fig. 8 is a diagrammatic view representing the signal system when the signal is positioned within the housing, and

50 Fig. 9 is a similar diagrammatic view representing the signal system when the signal has been extended from the housing to a display position.

Similar characters of reference are used 55 to denote corresponding parts throughout the accompanying drawings and the following description.

Referring more particularly to the drawings, the reference numeral 1 represents a 60 suitable housing which is provided at one end with the door opening 3.

A main standard 5 is vertically disposed 65 within the housing and a guide bar 6 is attached to the standard and extends horizontally therefrom in the direction of the door opening 3. This guide bar 6 is preferably square in cross section and has slidably mounted thereon a tubular rack bar 7, the outer end of this rack bar being rigidly attached to a signal 8.

An arm 15 extends laterally from the main standard 5 and carries a bracket arm 16 that extends horizontally of the housing and at right angles to the arm 15. The arm 75 16 is bifurcated for the reception of a slidable switch plate 17 and which is adapted to bear against and co-operate with a contact plate 18 which is rigidly secured to the outside of the arm 16. A bearing plate 19 is 80 attached to the inner face of the bracket arm 16 in overlapping relation to the movable switch plate, and serves to hold the switch plate in operative position within the bifurcation of the bracket arm 16. 85

The switch plate 17 is provided with a pair of vertically disposed elongated contacts 20 and 21, a pair of horizontally disposed elongated contacts 22 and 23, and an elongated contact 24 is disposed medially 90 and horizontally of the switch plate. The fixed contact plate 18 is provided with contact points 25, 26, 27, 28, 29, 30 and 31 that are adapted to co-operate with the contacts on the switch plate 17 to alternately complete the circuit through the primary and secondary circuits as will be described hereinafter.

This movable switch plate 17 is connected to a substantially U-shaped bracket arm or 100 bar 32 through the medium of a yieldable connection 33 which, in this instance, is in the shape of a comparatively stiff coil spring positioned around a pair of studs 34 carried by the switch plate 17 and the bracket arm 105 32, respectively. The outer angular ends of the bracket arm 32 are each provided with a square opening 35 for the reception of the

supporting bar 36, which latter is rigidly attached to the laterally extending arm 15 of the main standard 5, as at 37.

The laterally extending arm 15 and the outer end of the supporting bar 36 each support a spring latch 38. Each of these latches consists of a flat leaf spring 39 rigidly attached at one end, as at 40, and supporting at its opposite or free end a latch member 41, the outer terminal end of which is beveled, as indicated by the numeral 42. The inner end of the latch 41 is also beveled, as indicated by the numeral 43, but the angle of bevel is slightly less than that at the other end, and the latch member 41 is provided adjacent the beveled end 43 with a recess 44 adapted to receive the upper edge of the adjacent end 45 of the bracket arm 32.

The tubular rack bar 7 has rigidly attached to it a laterally extending trip arm 46 which has the upper edge of its outer terminal end oppositely beveled to provide a pointed edge 47 which is adapted to engage and cooperate with the beveled ends 42 of the spring latches. Coil springs 48 and 49 are positioned between the opposite ends 45 of the bracket arm 32 and the trip arm 46 and serve to move the bracket arm 32 in opposite directions as will be explained later.

Since the switch plate 17 is carried by the bracket arm 32, it will be apparent that as the trip arm 46 moves forwardly in the direction indicated by the arrow in Fig. 4 that the pointed end 47 will engage the trip member 41 and move the same upwardly and release the end 45 from the notch 44, whereupon the coil spring 48 will exert its expansive force to throw the bracket arm 32 forwardly, and consequently shift the switch plate 17 so as to bridge the secondary circuit and open the primary circuit as the signal is extended into a complete display position. When the signal has been extended to a complete display position, the automatic switch actuating means will assume the position shown in Fig. 3.

It will also be apparent from this that when the signal is moved back into the housing that the trip arm 46 will first come into engagement with the opposite spring latch member 41, at the same time compressing the spring 49, and by its further movement will release this spring latch member and consequently allow the expansive force of the spring 48 to throw the bracket arm 32 in the opposite direction and thus again shift the switch plate 17, so as to bridge the primary circuit.

In order to move the signal out of and into the housing, I have provided a suitable reversible motor 50 that may be conveniently supported within the housing and the armature shaft 51 is connected to the rack bar 7 through the medium of a suitable train of

gears 52. By operating the motor in one direction, it will be seen that the rack bar 7 will be extended out of the casing and by operating the motor in the reverse direction, the rack bar will be moved back into the housing.

Referring to Figs. 8 and 9, the operation of the signal appliance is briefly as follows: The diagrammatic view in Fig. 8 represents the normal position of the various relative parts of the signal system and with the signal positioned within the housing. When it is desired to signal to the rear of the motor vehicle of the intention of the motor vehicle operator to either stop or turn to the right or left, he pushes the button 66 which will move the contact plate 70 into engagement with the contact 68, thus completing the primary circuit. As soon as the primary circuit is completed, current will flow from the battery 72 through the wire 73 to field of the reversible motor 50, from the motor 50 through the wire 74 to the contact 26, through contact 23, contact 28, through wire 75 to the motor armature brush 76, through the contact plate 77 rigid on the armature shaft 51, through armature brush 78, through wire 79, to contact 25, and then through contact 22 to contact 27, through wire 80 to contact 29, to contact 30 through contact 24, through wire 81 to spring contact 70 and back through contact plate 68 and wire 82 to the battery 72, thus completing the primary circuit and at the same time actuating the motor 50 to extend the signal from the housing into a display position. This primary circuit will remain closed until the trip arm 46 moves beneath the latch member 41 at the outer end of the supporting bar 36 and disengages it from the end 45 of the bracket arm 32, whereupon the spring 48 will move the bracket arm longitudinally on the supporting arm 36 and simultaneously shift the switch plate 17 so as to open the primary circuit and close the secondary circuit at this point. This shifting of the switch plate 17 occurs at the instant that the signal reaches a complete display position.

As soon as the push button 66 is released and the contact plate 70 allowed to move back under its spring tension into contact with the contact 69, the secondary circuit will be completed and the current will flow, as indicated in Fig. 9, from the battery 72 through wire 73 to the field of the motor 50, from the motor field through wire 74 to contact 26, through contact 20 to contact point 25, through wire 79 to armature brush 78, through contact ring 77 and armature brush 76 to wire 75, and thence to contact point 28, through contact 21, contact point 27, wire 80, contact point 29, wire 83 to contact plate 69, contact plate 70, wire 81, contact point

- 30, contact 24, contact point 31, wire 84 to contact plate 68, and back through wire 82 to the battery, thus reversing the action of the motor 50 and causing the signal to move 5 back into the housing. When the signal has reached a complete inoperative position within the housing, the trip arm 46 at that instant will engage the innermost spring latch 38 and disengage it from the adjacent 10 end 45 of the bracket arm 32 and thus allow the tension spring 49 to move the bracket arm 32 longitudinally of the supporting arm 36 and at the same time shift the switch plate 17 to automatically open the secondary 15 circuit and close the primary circuit at this point so that the latter may be completely closed the next time the push button 66 is pushed in and the contact 70 moved into engagement with contact 68.
- 20 From the foregoing description, taken in connection with the accompanying drawings, it is to be understood that such changes in construction and arrangement of parts may be made when desired as are within the scope 25 of the appended claim.

I claim:—

A device of the character described comprising a frame having a supporting bar, a switch operating member extending along said bar and having end portions extending 30 at an angle and slidably mounted on said bar, an operating member slidable on said bar between said end portions, coiled springs on said bar between said operating member and end portions, and spring 35 latches carried by the frame at the opposite ends of said bar to engage and hold said end portions alternately, said latches and operating member having co-operable portions whereby the movement of the operating member in either direction will, in contacting with the corresponding latch, move the latch to releasing position.

In testimony whereof I have signed my name to this specification in the presence of 50 two subscribing witnesses.

CHARLES M. HEID.
